ADJUSTABLE SHELVING UNIT

Louis Maslow, Huntsville Road, Dallas, Pa. 18612

Filed May 2, 1968, Ser. No. 11,758

Term of patent 14 years

Int. Cl. D6—01

U.S. Cl. D80—10

FIG. 1.

FIG. 2.

FIGURE 1 is a perspective view of an adjustable shelving unit, shown by my new design, it being understood that the serpentine shaped brace wire is continuous throughout the area indicated in broken line; and

FIGURE 2 is an end elevational view thereof, the broken lines indicating an alternate and additional position for the shelving.

I claim:

The ornamental design for an adjustable shelving unit, substantially as shown and described.
